UNITED STATES PATENT OFFICE.

ARTHUR WHITCRAFT, OF ROCHESTER, NEW YORK, ASSIGNOR TO AMERICAN MANGANESE STEEL COMPANY, OF AUGUSTA, MAINE, A CORPORATION OF MAINE.

TEMPORARY SECTIONAL RAILWAY-TRACK.

1,281,451.

Specification of Letters Patent. Patented Oct. 15, 1918.

Application filed May 6, 1918. Serial No. 232,679.

To all whom it may concern:

Be it known that I, ARTHUR WHITCRAFT, a citizen of the United States, and a resident of Rochester, in the county of Monroe and 5 State of New York, have made and invented certain new and useful Improvements in Temporary Sectional Railway-Tracks, of which the following is a specification.

My invention relates to sectional track designed to be used with steam shovels and in 10 similar service wherein a temporary track, and one which may be readily put in place and as readily taken up or moved from one place to another, in order that the steam shovel or other device may be moved along 15 the track into a position adjacent the bank to be dug away, is desired. Such sectional track is also commonly used at places where the contents of cars are to be dumped, and, 20 in fact, in any place and in any service where a temporary railway track capable of being readily put in place and taken up and moved to a new location is deemed necessary or desirable.

25 The principal object of my invention is to provide a sectional track made up of a plurality of separate straight rails arranged in alinement with one another and in which an improved form of joint is provided between the ends of successive rails, the connection or joint being pivotal in character and somewhat loose so that successive rails may be arranged at an angle with one another and a certain degree of curvature thus 30 provided for in the track as installed, while still maintaining a connection between successive rails of sufficient strength and permanency to permit the steam shovel or other vehicle to run thereupon without danger of 35 derailment.

40 A further object of my invention is to provide a sectional track in which the separate rails are formed from cast metal, preferably cast manganese steel, and in which 45 the means whereby a pivotal connection is provided between successive rails is formed integrally with the rail sections; and in which said separate rails are also preferably provided with integrally formed lugs located upon their inner sides whereby the 50 ends of suitable spacing members may be

connected with two lines of rails, to thereby keep them a proper distance apart and maintain the proper gage of the track after it is installed.

55

A further object of my invention is to provide a sectional or temporary railway track in which one end of the bearing portion or tread of each rail extends beyond the end of the base portion of the next adjacent rail; and in which, preferably, the end of the tread of one rail is or may be supported by the base portion of the next following rail; while at the same time maintaining the pivotal connection between successive rails 60 and thus permitting such an amount of curvature in the track as may be necessary in order to bring the device operating thereupon into proper position.

65

With the above and other objects in view, 70 my invention consists in the improved sectional track and subordinate and auxiliary parts and features thereof, illustrated in the drawing accompanying and forming a part of this specification, the same being described at length in the following specification and particularly claimed at the end thereof; and in such variations and modifications of the particular embodiment of my invention illustrated and described as will 75 be obvious to those skilled in the art to which my invention relates.

75

Referring to the drawing wherein the preferred embodiment of my invention is illustrated:

85

Figure 1 is a view showing a portion of my improved sectional track in plan;

Fig. 2 is a view showing a section taken upon vertical transverse planes indicated by the broken line 2, 2, Fig. 1;

90

Fig. 3 is a fragmentary view showing the meeting ends of two successive rails and the joint between them, in side elevation;

Fig. 4 is a view showing a section taken upon a vertical transverse plane indicated by the line 4, 4, Fig. 3;

95

Fig. 5 is a view showing the end of one rail, and one member of the pivotal connection between successive rails, in perspective;

Fig. 6 is a similar view showing the end 100 of the next adjacent rail; and,

Fig. 7 is a view showing a section through

the joint and upon a horizontal plane indicated by the line 7, 7, Figs. 3 and 4.

Referring to the drawing, my improved sectional track is made up of two lines of 5 separate rails 8, the ends of which are pivotally connected with each other; the rails which form each line being frequently referred to herein as being arranged in alinement although the pivotal connections be- 10 tween the meeting ends of successive rails are so designed, as will hereinafter appear, as to permit each rail to be arranged at a slight angle to the next preceding rail, in order that such curvature as may be necessary or desirable in order to bring the shovel or other device into proper relation with the work to be done may be provided for in the track when installed. The separate rails are preferably made in comparatively 15 short lengths, and straight, although they may obviously be made curved in form to provide for excessive curvature in the track when installed, or in portions thereof; and the track formed by the two lines of rails 20 will ordinarily rest upon suitable cross ties, not shown, although in certain types or kinds of service the rails may rest directly on the ground.

The two lines of rails are kept at the 30 proper distance apart to maintain the proper gage of the track by means of spacing members 9 the ends 10 of which, in the form of my invention shown, are bent downward and enter holes 11 provided in lugs 12 35 formed upon the inside of the rails; two such lugs being preferably provided upon each separate rail, and two spacing members, as shown, being preferably used with each pair of rails. The separate rail sections 8 are preferably made from cast metal, such, for example, as cast manganese steel; in which case the side lugs 12, as well also as the lugs and other features hereinafter described whereby pivotal connections are 40 provided for at the ends of the rails and between each rail and the next following rail, are formed integrally with the rail; each rail with its side lugs and joint members at its ends being thus a single integral 45 structure whereby a temporary track which is simple in construction, and one which may be installed and removed at a minimum of trouble and expense, is secured.

The rail sections designated as a whole by 50 the reference numeral 8 are shown as of the ordinary standard section, that is, as comprising a base portion 13, a centrally disposed web 14, and a head 15 supported by and extending along said web. The web, however, 55 and also the head supported thereby, extend beyond the end 16 of the base at one end of the rail, as best shown in Fig. 5; and terminates short of the end 17 of the base at the other end of the rail, as best shown 60 in Fig. 6. The lower portion of the web at

the end of the rail where it extends beyond the base is cut away, as shown at 18, in order that the end of the web referred to may extend over or overlap the base of the next succeeding rail, and be supported by 70 the said base portion should the end of the rail first referred to tend to move downward, as will be understood from Figs. 3, 5 and 6. The cutting away of the under side of the web in question, in addition to providing 75 for the support of the end of one rail by the adjacent end of the next following rail, secures a construction in which the heads of successive rails align with one another; and also a construction in which the various 80 surfaces at which two successive rails contact with each other at the joint between them are in different planes, or in which the several contacting surfaces are so arranged as to break joint, as will be appreciated. 85 While the ends 19, 20 of the web and of the head of the rail are illustrated as inclined relatively to the longitudinal axis of the rail, such ends may, if desired, be so cut off as to lie in transverse planes at right angles 90 to the axis of the rail should such a construction be deemed preferable or desirable.

The joint whereby a pivotal connection is secured between the meeting ends of successive rail sections 8 is shown as comprising 95 lugs located adjacent the end of one rail, and projections located adjacent the end of the other rail and adapted to engage and interlock with said lugs; the entire joint forming mechanism and all the elements 100 and parts thereof being permanently associated with the rails, so that there are no auxiliary parts separate from the rails which have to be used for securing the rails together in installing the track; from which 105 it follows that the track may be put in place, and taken up and moved to another location, with a minimum of effort.

Referring more particularly to the pivotal connection or joint in question, the reference numeral 21 designates two lugs disposed upon opposite sides of the web 14 of a rail, and located adjacent the end thereof at which the head terminates short of the end of the base and between the end of the head and the end of the rail; said lugs being shown as formed integrally with and extending upward from the base 13 of the rail. These lugs are spaced apart from one another because of their arrangement upon 115 opposite sides of the web 14; the space between them is preferably closed by a bottom wall formed by the base 13 at the end of the rail at which they are located, thus providing a recess having a closed bottom between 120 the lugs; and said lugs are provided with recesses or openings 22 leading downward from their top walls and the bottoms of which two recesses, considered together, provide a seat extending transversely of the 130

end of the rail here referred to and adapted to receive the laterally extending projections 23 of the other rail.

- 5 The laterally extending projections 23 of the second rail are located upon opposite sides of the web 14, and at the end of the rail at which the web extends beyond the end of the base, as clearly shown in Fig. 5. The end of the web lies between the lugs 21, 10 and the projections 23 lie within the transverse seat provided by the bottoms of the recesses 22, when the ends of two adjacent rails are connected together through and by means of the joint in question; and the bottom wall 18 where the end of the web is cut 15 away is at such a height that it will contact with and rest upon the bottom wall of the recess between the lugs 21 in the embodiment of my invention illustrated; from which it 20 follows that the end of the rail shown in Fig. 5 will be supported by the base of the rail shown in Fig. 6, when the two are joined together in the manner illustrated in Fig. 3. It will be appreciated, however, that two 25 successive rails will be pivotally connected with each other through and by means of the lugs 21, and the projections 23 fitting into the recesses 22, even though the bottom of the pocket or recess between the lugs 21, 30 omitted and an open bottom recess used in lieu thereof; the supporting feature whereby the end of one rail is supported by the base of the next being independent of the joint between the meeting ends of the rails.
- 35 It will be observed that there is considerable looseness or play between the various elements which form the joint or connection between the rails, which feature is provided in order that a rail may be swung laterally, 40 and arranged at an angle to the preceding rail, thus providing joints which will permit a curved or sinuous track to be installed, and its curvature changed to suit the necessities of each particular case. A comparatively 45 small amount of looseness, however, will be sufficient to provide for such degrees of curvature as are ordinarily required in practice, and such looseness will in no way interfere with the use of the track on straight stretches where no curves have to 50 be provided for.

The rail sections are obviously connected with one another in a positive manner, and in such a way that they cannot become accidentally disconnected, notwithstanding the looseness at the joints above referred to; and curved rail sections may obviously be employed in case the permissible looseness at the joints is found to be insufficient to provide the degree of curvature required in any particular case, or in any particular service.

Having thus described and explained my invention, I claim and desire to secure by Letters Patent:—

- 65 1. In a sectional track, a rail having a

base, a centrally disposed web, and a head terminating short of the end of the base; a second rail having a base, a centrally disposed web extending beyond the end of the base and the lower portion of which is cut 70 away so that said web may extend over and be supported by the base of the first-mentioned rail, and a head adapted to aline with the head of said first-mentioned rail; and means for providing a pivotal connection between the meeting ends of said rails. 75

2. In a sectional track, a rail formed from cast metal and having securing devices located one at each of its ends and formed integrally therewith, and which securing devices are adapted to engage with similarly located securing devices formed integrally with abutting rails, to thereby pivotally connect successive rails together. 80

3. In a sectional track, a rail formed from cast metal and having means at its ends formed integrally therewith whereby the same may be pivotally connected with other rails, and having also a lug formed upon its inner side and integrally therewith to receive the end of a spacing member. 85

4. In a sectional track, two rails formed from cast metal and having means at their ends formed integrally therewith whereby they may be pivotally connected with other rails, and each of which rails is provided with two lugs formed integrally therewith and located upon its inner side and one adjacent each of its ends; and two transversely extending spacing members extending between, and the ends of which are pivotally connected with, said lugs. 95

5. In a sectional track, a rail formed from cast metal and having a base, a centrally disposed web extending beyond the end of the base at one end and terminating short of the end of the base at the other end, a head supported by the web, and securing members adjacent the ends of the rail and formed integrally therewith and adapted to detachably engage similarly located securing members upon abutting rails, to thereby pivotally connect successive rails together. 105 110

6. In a sectional track, a plurality of rails arranged in alinement and each of which has a base, a centrally disposed web extending beyond the end of the base at one end and terminating short of the end of the base at the other end, and a head supported by the web; and two separable fastening members 120 formed integrally with the respective ends of abutting rails and adapted to engage each other, whereby the end of each rail is pivotally connected with the end of the next following rail, the end of the web of each 125 rail extending over and being supported by the base of the next following rail.

7. In a sectional track, a plurality of rails arranged in alinement and each of which has a base, a centrally disposed web extending 130

beyond the end of the base at one end and terminating short of the end of the base at the other end, and a head supported by the web; two separable fastening members 5 formed integrally with the respective ends of abutting rails and adapted to engage each other, whereby the end of each rail is pivotally connected with the end of the next following rail; and means whereby that end 10 of each rail which has the web extending be-

yond the base is supported by the end of a following rail having the web terminating short of the end of the base.

Signed at Pittsburgh in the county of Allegheny and State of Pennsylvania, this 15
7th day of March A. D. 1918.
